(57) **CLAIM**

The ornamental design for a multi-function collapsible exercise apparatus, as shown and described.

DESCRIPTION

FIG. 1 is a front perspective view of a multi-function collapsible exercise apparatus, showing my new design;

FIG. 2 is a rear perspective view thereof;

FIG. 3 is a front elevational view thereof;

FIG. 4 is a rear elevational view thereof;

FIG. 5 is a left-side elevational view thereof, the right-side elevational view being a mirror image thereof;

FIG. 6 is a top plan view thereof; and,

FIG. 7 is a bottom plan view thereof.

The broken lines in the figures depict portions of the multi-function collapsible exercise apparatus that form no part of the claimed design.

1 Claim, 7 Drawing Sheets
